BY Missouri ATTY.

UNITED STATES PATENT OFFICE.

WILLIAM F. STONE, OF PORTLAND, MAINE, ASSIGNOR TO NATIONAL METAL SEAL CORPORATION, A CORPORATION OF MAINE.

CRIMPING-TOOL.

1,305,752.

Specification of Letters Patent. Patented June 3, 1919.

Application filed July 16, 1914. Serial No. 851,387.

To all whom it may concern:

Be it known that I, WILLIAM F. STONE, a citizen of the United States, residing at Portland, county of Cumberland, State of 5 Maine, have invented certain new and useful Improvements in Crimping-Tools, of which the following is a specification.

This invention relates to crimping tools and particularly to a crimping tool for 10 clenching the sealing lugs of a closure under the shoulder of a vessel neck.

My present invention as a whole is a development of and improvement upon the crimping tool of the Chellis Patent No. 15 1,067,797 granted July 22, 1913. Although both tools are adapted to the crimping of the same or substantially similar seals and both have the same general object in view, the tool of my present invention differs in essential 20 features from the patented tool.

The construction and operation of my present invention will be more fully disclosed in the specification that follows. In the drawings forming a part of that specification I have shown as an illustrative embodiment a form of tool which I have found satisfactory in practice. Throughout specification and drawings like reference numerals are correspondingly applied, and in 30 these drawings:

Figure 1 is an elevation in vertical section, of a crimping tool in accordance with my invention and illustrating the tool in crimping position upon a vessel mouth and prior to crimping.

Fig. 2 is a plan section of the crimping jaws.

Fig. 3 is a section at right angles to Fig. 1 showing the tool prior to clenching a 40 closure.

Fig. 4 is a view similar to Fig. 3 showing the tool after clenching a closure.

Fig. 5 is a transverse section on the line 5-5 of Fig. 3.

Fig. 6 is a section showing a closure and vessel mouth after crimping, and

Fig. 7 is a view of one form of closure.

The crimping tool as a whole is preferably portable so that it can be carried from 50 can to can to clench the seals which have been previously placed over the delivery opening of the can nozzle.

I have indicated at 1 a stationary spindle and guide having an enlarged circular base 55 or head 2 which is circularly cut out upon

its under face as indicated and provides a stationary die or sealing head for the closure against which the seal bears.

Surmounting the head 2 is a stationary clenching handle 3 having an integral sleeve 60 or collar portion 4 encircling the lower end of the spindle and resting upon the head 2. The sleeve 4 provides a seat and stop for a cylindrical slide 5 normally resting upon the upper edge of the sleeve and reciprocable 65 vertically along the spindle 1.

The handle 3 is transversely recessed on its upper face near its inner end as indicated at 6 (Fig. 1) and has a bore in which fits an adjusting screw 7 which pins one end of a 70 link 8 to the handle 3. The screw 7 has an eccentric portion on which one end of the link 8 is pivoted. The other end of the link is connected at 9 to the end 10 of an operating handle 11 pivoted at 12 in suitable ears 75 projecting from the upper end of the slide 5. The connections described serve to lift the slide 5 when the handle 11 is depressed.

The upward movement of the slide 5 is resisted by a coil spring 13 wrapped about 80 a pin 14 interposed between the offset upper edge of the slide and a stationary handle 15 fastened to said spindle above the slide. The action of the spring 13 is therefore to return the slide 5 to normal position after each 85 reciprocation.

The slide 5 has two oppositely disposed lateral wings 16. Pivoted between its ends at 17 to each wing is a laterally movable crimping jaw 18. The jaws 18 are normally 90 held in expanded position by spring pressed pins 19 seated in sockets in the jaws below the pivots 17 and bearing against the slide 5. At its lower end each jaw terminates in a segmental upturned crimping edge 22 95 which is circularly grooved at 23 to receive and clench the sealing lugs of the closure when the jaws are brought together.

The jaws above the pivots 17 are beveled outwardly and upwardly as indicated at 24. 100 The inclines 24 terminate in outwardly inclined faces 25 which have a greater pitch than the faces 24. The faces 25 define with the opposite inwardly curved faces 26 of the head 27 of the stationary handle 15 recesses 105 or pockets in which are received rolls 28 having their studs journaled in suitable ears on the head of the handle 15. The handle 15 embraces the top end of the spindle and has a shouldered bearing thereon. The spin- 110

dle is surmounted by a cross head 29 secured thereto and having a bearing on the handle 15.

The can or other containing vessel A has 5 a nozzle or neck portion B terminating at its top end in a horizontal circular seat C having a downturned overhang D bent back and upwardly upon itself at its lower edge in the form of a continuously recessed an- 10 nular rim E spaced from the neck.

One form of closure on which this crimping device is adapted to be applied consists of a cap F overlying the delivery opening of the nozzle, which opening is sealed by a suitable packing G carried by the cap, see Figs. 1, 3 and 4. The cap has a circumferential depending skirt or flange H from which engaging fingers J and K depend. The fingers J are clenched permanently as hinge lugs 15 while the fingers K are lightly engaged as deformable lugs. These deformable lugs 20 may be formed as at K¹ in Fig. 6.

The number of engaging fingers and their relative arrangement about the circumference of the cap may be varied. In the form of closure shown in Fig. 7 there is pivoted 25 at P to the cap F a laterally swingable cover L provided with a spring locking lip M at a point substantially opposite the pivot P. 30 This locking lip is not crimped by the clenching jaws but is formed before the closure is applied to the container.

In use, the crimping tool is carried from can to can by means of the stationary handle 35 which simply serves as an arm whereby the tool may be carried. A closure is placed in position over the delivery opening of the filled can and the tool placed around the can neck in the manner shown in Fig. 3. This 40 positions the head or stationary die 2 on the top of the cap with the crimping jaws held free of the can by reason of the spring pressed pins 19. The stationary clenching handle 3 is grasped with one hand to steady 45 and properly center the tool on the can head and the operating handle 11 is grasped with the other hand and depressed. The depression of the handle 11 through the link 8 draws up the slide 5 on its guide 1 against 50 the tension of the coil spring 13. This movement of the slide draws up the crimping jaws which are pivoted thereto between their ends. As the cam faces 25 of the jaws 55 18 ride up past the rolls 28 the upper ends of the jaws are forced outwardly. This causes the lower ends of the jaws to move inwardly toward each other and brings their die portions 22 between fingers J and the nozzle neck, with said fingers lying in the 60 segmental grooves 23. The continued upward and inward movement of the jaws causes the grooves 23 to turn the fingers in and under the rim E of the nozzle. The cap is now clenched upon the nozzle. As soon 65 as pressure is removed from the operating

handle 11 the spring 13 tends to automatically return the slide 5 and thus the handle and jaws to original position.

Where the number and arrangement of the fingers J differ from the form shown in the drawings, the crimping dies 22 may be changed slightly to accord. Various other modifications in the form and construction of my device may obviously be made, all without departing from the spirit of my invention if within the limits of the appended claims.

What I therefore claim and desire to secure by Letters Patent is:

1. A crimping tool for crimping the lugs 80 of a closure beneath the shouldered mouth of a containing vessel, comprising a spindle having a head adapted to rest upon the closure, a slide reciprocable on said spindle, a stationary clenching handle mounted upon 85 said spindle, a pair of crimping jaws pivoted between their ends to said slide and having their lower ends formed as crimping surfaces, an operating handle fulcrumed on 90 said slide and connected with said fixed clenching handle, means having a sliding engagement with the upper ends of said crimping jaws effective to expand said upper ends and contract said lower ends when the slide is raised, and means for automatically 95 returning said slide to original position after each reciprocation.

2. A crimping tool for crimping the lugs 100 of a closure beneath the shouldered mouth of a containing vessel, comprising a spindle, a slide reciprocable on said spindle, a stationary clenching handle mounted upon said spindle, a pair of crimping jaws pivoted between their ends to said slide and having their lower ends formed as crimping surfaces, an operating handle fulcrumed on 105 said slide and having an adjustable link connection with said fixed clenching handle, means having a sliding cam engagement with the upper ends of said crimping jaws, 110 effective to expand said upper ends and contract said lower ends when the slide is raised, and means effectively disposed for automatically returning said slide to original 115 position after each reciprocation.

3. A crimping tool for crimping the lugs 120 of a closure beneath the shouldered mouth of a containing vessel, comprising a spindle having a head adapted to rest upon the closure, a slide reciprocable on said spindle, a stationary clenching handle having a collar portion embracing said spindle between said head and slide and providing a stop to limit the downward movement of said slide, a pair of oppositely disposed lateral wings on said 125 slide, a pair of crimping jaws pivoted between their ends to said wings and having their lower ends formed as crimping surfaces, an operating handle fulcrumed on said slide and having a link connection with 130

5 said fixed clenching handle, means having a roller bearing with the upper ends of said crimping jaws, effective to expand said upper ends and contract said lower ends when the slide is raised, and a spring wrapped pin effectively disposed for automatically returning said slide to original position after each reciprocation.

10 4. In crimping means, a movable element, a pair of laterally movable members pivoted between their ends to said movable element at opposite sides thereof, each member having an outwardly directed surface at its upper end and an inwardly curved substantially semi-circular crimping portion at its lower end, an operating handle pivoted to said movable element and a link connected thereto and fulcrumed below said pivot for moving said movable element in one direction, a stationary member having outwardly curved walls, and rolls interposed between said walls and the inclined surfaces of said pair of pivoted members for moving the upper ends of said members laterally.

15 5. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, and a pair of oppositely disposed inwardly movable seating members pivoted to said slide.

20 6. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

25 7. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

30 8. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, and a pair of oppositely disposed inwardly movable seating members pivoted to said slide.

35

6. In apparatus for seating closures upon containers, a stationary holding member comprising a head disposed to bear upon the closure, and a guiding stem, a stationary handle sleeved about said stem above said head, a slide reciprocable upon said stem, and limited in its downward movement by the sleeve portion of said stationary handle, a movable handle pivoted to said slide and disposed in digitally spannable relation to the stationary handle whereby both handles may be grasped in one hand, and a pair of oppositely disposed inwardly movable seating members pivoted to said slide.

40 7. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

45 8. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

50 9. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

55 10. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.

60 11. In apparatus for seating closures upon containers, a stationary holding member comprising a head disposed to bear upon the closure, and a guiding stem, a stationary handle sleeved about said stem above said head, a slide reciprocable upon said stem, a movable handle pivoted to said slide and disposed in digitally spannable relation to the stationary handle whereby both handles may be grasped in one hand, a pair of oppositely disposed inwardly movable seating members pivoted to said slide, and a link connected to said movable handle and fulcrumed upon said stationary handle below the pivot for the movable handle.
